UNITED STATES PATENT OFFICE.

RAYMOND BURNHAM, OF MINNEAPOLIS, MINNESOTA. ASSIGNOR TO GEBHARDT METER COMPANY, A CORPORATION OF ILLINOIS.

MAGNETIC ENGINE.

1,144,998.

Specification of Letters Patent.

Patented July 6, 1915.

Original application filed November 21, 1907. Serial No. 403,126. Divided and this application filed April 15, 1913. Serial No. 761,320.

To all whom it may concern:

Be it known that I, RAYMOND BURNHAM, a citizen of the United States, residing at Minneapolis, in the county of Hennepin and State of Minnesota, have invented certain new and useful Improvements in Magnetic Engines, of which the following is a specification.

My invention relates to magnetic engines and is a division of my co-pending application filed November 21, 1907, Serial No. 403,126.

The invention has for its primary object the provision of an improved magnetic engine, which shall have improved means for causing mechanism without a sealed chamber to be actuated by movable parts therewithin.

With the above and other objects in view this invention consists substantially in the combination, arrangement, and construction of parts all as hereinafter described, shown in the accompanying drawings which form a part of this specification, and more specifically set forth in the subjoined claims.

In the drawings: Figure 1 is a vertical section of my invention taken approximately on the line 1—1 of Fig. 3, looking in the direction indicated by the arrows, and showing it applied to a steam meter. Fig. 2 is a front elevation of my invention with a part of the dial broken away and showing it in combination with a steam meter. Fig. 3 is a horizontal section taken approximately on the line 3—3 of Fig. 2 looking in the direction indicated by the arrows, and showing it in combination with a steam meter.

In the present exemplification of my invention it is illustrated as actuated by a steam meter which is operated by a steam pipe 1 and attached to the steam pipe by means of bushings 2 and 3, and the invention is further illustrated as adapted to the driving of an indicator arm about a dial, although it may be used in many other ways. A Pitot tube comprising a neck 4 and an elbow 5, is secured within the bushing 2 and has its mouth turned against the current of steam in the pipe 1. The neck 4 of the Pitot tube communicates with the float chamber 6, containing water of condensation. An arm 8 pivoted intermediate its extremities to a support 9 is operatively connected at

one of its ends to a float 7 supported by the water in the chamber 6. The opposite end of the arm 8 has pivotal connection with the lower end of a rod 10 the upper end of which rod passes through a liquid and steam-tight neck 11 into a liquid and steam-tight chamber 12, where it is pivotally secured to a crank-arm 13 arranged to rotate a magnet 14 pivoted in the chamber 12 upon a shaft 15. The chamber 12 is preferably provided with a steam-tight cap 16 whereby access may be had to the parts within the chamber 12 and, if it be found convenient, the cap may be recessed as at 17 to form a bearing for one end of the shaft 15, the other end of the shaft 15 being preferably pointed and supported in the opposite wall of the chamber 12, as shown in Fig. 3. Other forms of construction may obviously be employed for operatively connecting the magnet 14 with the float 7 so as to move the magnet when the float moves. The rotation of the magnet 14 effects a corresponding rotation of a magnet 18 mounted outside the chamber 12 and near enough to the casing to be within the magnetic influence or field of the magnet 14, the two magnets being preferably arranged to rotate in parallel planes. The magnet 18 is mounted upon an arbor 19, one end of which is supported in a wall of the chamber 12 and the other end in a bracket 20. The arbor 19 carries a gear wheel 21. Another arbor 23 carries a pinion 22 in mesh with the gear wheel 21, the pinion being considerably smaller than the gear wheel 21, and the arbor 23 being journaled at one of its ends in the wall of the chamber 12 and at its other end in the bracket 20. A dial case 27^a is positioned adjacent the chamber 12 and through its back plate 24 the outer end of the arbor 23 projects. An indicator arm 25 is carried by the projecting end of the arbor 23 and is positioned to register with various graduations 26 upon a dial 27, contained in the dial case 27^a. From this description it will be seen that a very slight movement of the float 7 will be magnified through the gear 21 and the pinion 22 into a relatively large movement of the indicator arm 25. In this manner a readable indication of the slightest movement of the float 7 is exhibited upon the dial 27. Various mechanisms other than the multiplying gear and indicating apparatus

2
just described may, of course, be driven by the magnetic engine.

The upper part of the float chamber 6 is connected with the steam pipe 1. The end 5 of this upper passage includes a piece of tubing 28 positioned in the bushing 3, protruding within the steam pipe 1 and having its protruding extremity angled as at 27. As constructional features of the apparatus 10 the two bushings 2 and 3 may be made as parts of unions or nuts 29 and 30, whose companion members are shown at 31 and 32. These latter are shown as connected respectively by tubes 33 and 34 with the upper 15 and lower inlets of the float chamber 6. If desired a condensation coil 35 may be inserted with its extremities connected to the tubes 33 and 34, as shown in Fig. 1. An automatic air relief 36 may be provided 20 communicating with the chamber 6, and access to the chamber 6 is provided by means of plugs 37 and 38.

The steam meter is shown and described in the drawings for the purpose of illustrating my invention operatively connected to a medium whose variations are to be indicated, but it is not intended to restrict the use of my magnetic engine to combination with a steam meter, it being obvious from the foregoing 25 description that it may be used in combination with a great number of other mechanisms. Neither is it intended to restrict the use of my magnetic engine to the operation of a magnetic indicator, for it 30 may be operatively connected to a variety of other devices.

In the accompanying drawings and in the foregoing description is set forth the preferred embodiment of my invention, but it is obvious that one skilled in the art may modify it without departing from the principle thereof.

I claim:

1. The combination with a float chamber, 15 of a pivotally mounted float therein, a movable magnet connected with the float, an auxiliary chamber inclosing said magnet and in communication with said float chamber through hermetically sealed from the atmosphere, and a second magnet outside of said auxiliary chamber but within the magnetic field of said first-named magnet for movement thereby.

2. The combination with a container for 55 a changeable medium, comprising a float chamber, a pivotally mounted float in said chamber, a magnet, in connection with said float, an auxiliary chamber inclosing said magnet hermetically though in communication with said float chamber, a second magnet outside of said auxiliary chamber but

within the magnetic field of said first-named magnet for movement thereby, and an indicator connected to said outside magnet.

3. The combination with a float chamber, a 65 pivotally mounted float therein, an oscillating magnet connected thereto, an auxiliary chamber hermetically inclosing said magnet, a second magnet within the magnetic field of said first-named magnet, and indicating mechanism connected to said second magnet.

4. The combination of a float chamber, a 70 float in said chamber, an oscillating magnet, a chamber communicating with the float chamber and inclosing the magnet, an arm 75 upon the magnet, a connecting rod connected at one end to one end of said arm, a float lever connected at one end to the opposite end of the connecting rod, fulcrumed intermediate its extremities and connected at its 80 opposite end to the float, a second magnet within the magnetic field of the first magnet and adapted to be moved thereby, and indicating mechanism operatively connected to the second magnet.

5. The combination with a float chamber, 85 of a float in said chamber, a pivoted magnet, an auxiliary chamber communicating with the float chamber and inclosing the said magnet hermetically, an arm extending from the pivotal portion of said magnet, a link pivoted at its upper end to said arm, a float lever connected at one end to said float and pivoted at its other end to the lower end of said link, a fulcrum support for said float lever within the float chamber, a second magnet outside and near said auxiliary chamber within the magnetic field of said first-named magnet for movement thereby, and indicating mechanism connected to said 90 outside magnet.

6. The combination of a float chamber, a 95 pivotally mounted float in said chamber, a movable magnet, means operatively connecting the magnet to the float, a chamber communicating with the float chamber and hermetically inclosing the magnet, a graduated dial, an indicator arm for the dial, a second magnet within the magnetic field of the first magnet and adapted to be moved thereby, 100 a gear wheel fixed to the second magnet, and a pinion fixed to the indicator arm and meshing with the gear wheel.

In testimony whereof I have signed my name to this specification, in the presence of 115 two subscribing witnesses, on this 12th day of April A. D., 1913.

RAYMOND BURNHAM
